HOLDER FOR MATCH BOOKS

William S. Hutcheson, Omaha, Nebr.

Application February 27, 1950, Serial No. 8,170

Term of patent 14 years

(Cl. D80—9)

To all whom it may concern:

Be it known that I, William S. Hutcheson, a citizen of the United States, residing at Omaha, in the county of Douglas and State of Nebraska, have invented a new, original, and ornamental Design for a Holder for Match Books, of which the following is a specification, reference being had to the accompanying drawing, forming part thereof.

I claim:

The ornamental design for a holder for match books, as shown.

WILLIAM S. HUTCHESON.
